UNITED STATES PATENT OFFICE.

JAMES W. FITZGERALD, OF MAYSVILLE, KENTUCKY.

STALLION-SHIELD.

SPECIFICATION forming part of Letters Patent No. 521,462, dated June 19, 1894.

Application filed July 5, 1892. Serial No. 438,896. (No model.)

To all whom it may concern:

Be it known that I, JAMES W. FITZGERALD, a citizen of the United States, residing at Maysville, in the county of Mason and State 5 of Kentucky, have invented certain new and useful Improvements in Stallion-Shields; and I do declare the following to be a full, clear, and exact description of the invention, such as will enable others skilled in the art to which 10 it appertains to make and use the same.

This invention relates to improvements in stallion shields or devices to be worn by stallions to prevent masturbation or self abuse; and its novelty will be fully understood from the following description and claims when taken in conjunction with the annexed drawings, in which—

Figure 1 is a view of a horse showing my improvements in position thereon. Fig. 2 is 20 a perspective view of the shield removed showing one of the protection plates partly broken away. Fig. 3 is a plan view of the inner side, and Fig. 4 is a transverse sectional view.

In carrying out my invention I take a strip 25 A, of leather of a sufficient thickness and length and width to go beneath and across the belly of a horse. I then take a piece of thick sole leather B, as shown and a piece of 30 light leather, canvas or other suitable material as shown at C. The face piece C, is then provided with a bed of fine wire staples a, having blunt points or ends, and at suitable points in this bed of staples I arrange steel 35 points or tacks which should be of slightly greater length than the staples so that the steel points or tacks may sharply pierce the penis while the blunt staples will tend to prevent the tacks from seriously injuring the 40 penis though themselves having somewhat of a gentle pricking effect.

D, is a strip or sheet of metal which serves 45 as a back for the staples and tacks or points. This strip of metal is also designed to give shape to the shield carrying the points and hold it rigid or prevent any flexibility so that it will not lose its shape by being struck by the penis.

While it is desirable that there should be 50 no give or bending to the shield, and the strip D, of metal is principally employed for the purpose of holding the pricking points

and staples rigidly in a bowed position, yet as the shield must be worn day and night it is necessary that the metal strip be as light 55 as possible and yet accomplish the feature of rigidity.

After the metal strip has been placed between the face piece C, and the stiff leather back piece B, the two outer pieces are connected at their margins by a binding a', of leather or other suitable material which is secured by stitches b, passing through both the binding and the marginal edges of the pieces B, and C.

It is known that some horses in lying down put their hind legs beneath them and when wearing the shield they not only cut their limbs with the tacks or points but break down the staples at the ends of the shield. To overcome this objection I provide the bed of staples at each end with protecting plates E. These plates are preferably formed from tin or light sheet metal having a base flange c, by which they are secured to the face piece 75 C, by means of small rivets or other suitable fastening devices, and these plates have an overhanging flange or shield d, which overhangs the staples at each end of the shield as shown so that the horse in lying down can- 80 not cut or injure himself or break down or damage the staples.

It is obvious that the shape of these protecting plates may be changed according to the fancy of the manufacturer and they may 85 be made of any suitable material.

The shield comprising the face strip C, the stiff sole leather back piece B, and the interposed metal piece D, with the points and staples, is secured in a bowed position to the 90 belly strap or piece A, near opposite ends by means of a rivet F. These rivets are arranged in about the longitudinal center of the shield and belly piece respectively and the shield is further secured to said belly piece by two 95 more rivets G. These latter rivets are arranged nearer together or more toward the transverse center than the rivets F, and secure the shield to the belly piece adjacent the rear transverse edges of both pieces so 100 that the part carrying the pricking points and staples will be pitched slightly rearward so as to place the bed of staples in a position to receive the stroke of the penis and not

permit of the same striking the edges of the shield only, which in course of time serves to bend the shield and also the staples so as to encourage the habit rather than to stop it, 5 and I attach importance to the fact that the bed of staples is rigidly sustained by the employment of the metal plate and that said bed is held in such an inclined position that the top of the penis will strike flat against 10 the bed of points and staples and not against the edge of the shield as heretofore.

H, indicates loops which are arranged at opposite ends of the shield. These loops may be composed of straps of leather to receive 15 rings I, and may be secured in position by the rivets F, which secure the shield to the belly piece.

In practice any suitable means might be employed for suspending the shield in position on a horse, but in the present illustration I have shown the shield as secured beneath the belly by means of a harness composed of a collar strap K, having rings e, on 20 opposite sides, a strap L, passing down the back from the collar strap and connected with a crupper, a strap passing over the haunch and connected at one end with the back-strap and at the opposite end with the 25

rings in the ends of the shield and two side straps M, connecting the ends of the shield 30 with the rings in the collar strap. The various straps are provided with buckles so that the harness may be made adjustable.

Having described my invention, what I claim, and desire to secure by Letters Patent, 35 is—

1. A stallion shield having a bed of staples or pricking points and also having the protecting plates at opposite ends of said bed, substantially as specified. 40

2. The shield comprising the belly strap, the sole leather B, the leather or canvas C, the interposed metal strip D, the blunt staples and tacks or points arranged in the piece C, the combined pieces being secured near 45 opposite ends in a bowed manner to the belly strap and in the longitudinal center by rivets F, and said parts being also secured together near their inner longitudinal edges by staples G, substantially as specified. 50

In testimony whereof I affix my signature in presence of two witnesses.

JAMES W. FITZGERALD.
